INVENTOR

UNITED STATES PATENT OFFICE

100,606

DESIGN FOR AN ELASTIC FABRIC

Raymond K. Siner, Philadelphia, Pa.

Application May 20, 1936, Serial No. 62,734

Term of patent 3½ years

To all whom it may concern:

Be it known that I, Raymond K. Siner, a citizen of the United States of America, residing in Philadelphia, county of Philadelphia, and State of Pennsylvania, have invented a new, original, and ornamental Design for an Elastic Fabric, of which the following is a specification, reference being had to the accompanying drawing, forming part thereof, wherein,

Figure 1 is a plan view of a piece of unstretched elastic fabric showing my new design.

Figure 2 is a view of the elastic fabric shown

in Figure 1, showing the elastic fabric stretched to the elastic limit.

The characteristic feature of the design resides in a unit of three groups of loops each succeeding group diminishing in number and with each unit alternately reversed on the following line, as shown.

I claim:

The ornamental design for an elastic fabric, substantially as shown and described.

RAYMOND K. SINER.
